Des. 1496

Henry C. Thompson, of New York, N. Y.
Assignor to
Oppenford, Garret, Bonynge, &
Letters Patent No. 131, dated Nov. 19, 1861.

The schedule referred to in these Letters Patent and making part of the same:

So as when it may amend.

That it is known that John Q. Thompson, of the City, County, and State of New York, have invented or produced several and original Design for a Pattern to be wrought into Carpeting and other carpeting in colors similar to those painted on the drawings accompanying this specification, or in other colors substituted in the place of those painted on the drawings herewith; and I do hereby declare that the drawings accompanying this specification, do give and convey to any one skilled in the Art of Carpet weaving a more defined and thorough description of the nature of my invention than it is in the power of language otherwise to convey, and is sufficient to enable any one skilled in the Art of carpet weaving to use my invention

What I claim as my invention and desire to secure by Letters Patent, is the configuration of the design hereunto annexed, when made by being wrought into Ply Ingrain or other Carpeting, in the form similar to the drawings accompanying this specification.
